UNITED STATES PATENT OFFICE.

CHARLES E. SCRIBNER, OF CHICAGO, ILLINOIS, ASSIGNOR TO THE WESTERN ELECTRIC COMPANY, OF SAME PLACE.

ELECTRIC-ARC LAMP.

SPECIFICATION forming part of Letters Patent No. 559,408, dated May 5, 1896.

Application filed January 9, 1894. Serial No. 496,812. (No model.)

To all whom it may concern:

Be it known that I, CHARLES E. SCRIBNER, a citizen of the United States, residing at Chicago, in the county of Cook and State of Illinois, have invented a certain new and useful Improvement in Automatic Cut-Outs for Arc-Lamps, (Case No. 347,) of which the following is a full, clear, concise, and exact description, reference being had to the accompanying drawing, forming a part of this specification.

My invention relates to automatic cut-outs for electric-arc lamps. Its object is to provide a cut-out adapted to be brought into operation by the descent of the movable carbon to a predetermined point, in the consumption of the carbons, to create and maintain a short circuit about the lamp.

My invention is especially applicable to the type of electric-arc lamps commonly known as "open-circuit" lamps, in which the movable carbon is normally raised from the fixed carbon by the force of a spring, the approach of the movable carbon toward the fixed carbon, in order to create and regulate the arc, being effected by an electromagnet in shunt of the carbons. In this type of arc-lamps it has not heretofore been practicable to provide a switch adapted to be actuated by the descent of the carbon-rod to close the cut-out circuit—as, for example, by a stud or collar upon the carbon-rod coming to bear upon the switch—since the moment the lamp is thus short-circuited the carbon-rod is again raised by the regulating mechanism and the switch thereby opened.

My invention is designed to avoid this difficulty. I provide a switch spring or lever in position to register with a collar upon the carbon-rod at a predetermined point in the path of the collar, and a connection between the carbon-rod or the levers regulating and moving with it and the switch-lever adapted to move the switch-lever in the same direction as the carbon-rod with pressure, whereby when the lamp is cut out the switch-lever is pressed against the collar on the carbon-rod and rises with it, thus maintaining the cut-out contact. I am thus enabled to construct a very simple and perfectly-efficient cut-out.

My invention is represented in the accompanying drawing, wherein I have shown a simple form of open-circuit electric-arc lamp provided with my improved cut-out.

The arc-lamp consists, essentially, of a fixed carbon *a* and a movable carbon *a'*, the latter being carried upon a carbon-rod *c*, movable longitudinally in journals in the lamp-frame *b*. At one point the rod *c* passes through a clutch *d*, which is suspended from a lever *e*, which I term the "feeding-lever." This lever is fixed at one extremity to a flexible strap *e'*, so as to be movable. A flat spring *f* has one extremity fixed upon the lever *e* and the other attached to an adjustable hook *g*, whereby a constant force is exerted upon the lever *e*, tending to raise it and through it the clutch *d*, rod *c*, and carbon *a'*. A bracket *d'* is provided beneath the clutch *d*, upon which the latter may bear when it has been permitted to descend to a sufficient distance. Near its fulcrum the rod *e* carries an armature *h*, moving before the poles of an electromagnet *i*.

The carbon-rod *b* is provided with a head or collar *b'* at its upper extremity, which is adapted to engage the free extremity of an insulated pivoted switch-lever *k* when the rod has descended to the requisite distance in feeding the carbon *a'* as it is consumed. This position of the collar *b'* is shown in dotted lines in the drawing.

The switch-lever *k* is connected with feeding-lever *e* by means of an insulating-stud *l*, fixed in the feeding-lever. The switch-lever *k* is maintained in contact with stud *l* by a spring *m*. The stud *l* is attached to lever *e* at a greater distance from the lever's fulcrum than the point of support of clutch *d*, and the stud *l* bears upon the switch-lever *k* at a point nearer the fulcrum of the latter than the contact-point which it carries. By this arrangement the contact point or surface of lever *k* is caused to move through a greater range in following the movements of lever *e* than the clutch *d* and the carbon-rod which it grasps.

The circuit through the lamp is of the usual character, the incoming or positive main being connected with the carbon-rod *b* or the frame of the lamp and the other with the lower carbon *a*. The magnet *i* is of high re-

sistance and is connected in shunt of the carbons. The switch-spring *k* is connected with the outgoing or negative main.

The normal position of the lamp is that indicated in the drawing, the carbon *a'* being raised through the medium of carbon-rod *b*, clutch *d*, lever *e*, and spring *f*. When current is first sent through the lamp, magnet *i* is excited and attracts its armature *h*, lowering the clutch *d* until it strikes the bracket *d'* and releases the carbon-rod *b*, thus permitting the carbons to come in contact. At the instant of their contact the lamp is short-circuited and the magnet *i* is de-energized, where-
15 by the spring *f* is again permitted to raise the carbon *a'*, thus forming the arc. The spring *f* is adjusted with relation to the strength of magnet *i* to maintain the desired length of arc between carbons *a a'* in the usual manner.
20 When, as the carbons are consumed, the rod *b* descends until the collar *b'* touches the extremity of switch-lever *k*, a short circuit is formed about the lamp, extending from the carbon-rod *b* through the switch-lever *k* to the outgoing main. Magnet *i* is thus de-energized
25 and releases its armature *h*. The lever *e* rises, raising with it the rod *b* and the collar *b'* thereon, but at the same time, through the stud *l* forcing the switch-lever *k* upward against
30 collar *b'* at a higher rate of movement than the clutch *d*, tends to raise the rod. The rod is thus raised through the clutch, maintaining at the same time a firm contact with switch-lever *k*, thus preventing the rupture
35 of the short circuit about the lamp.

It will be clear that other means might be adopted of communicating to switch-lever *k* the desired movement with relation to the feeding mechanism or the feeding-lever of
40 the lamp to attain the same general result, perhaps with equal efficiency. I therefore do not limit myself to the form shown; but

I claim, broadly, as new and desire to secure by Letters Patent—

45 1. The combination with the carbon-rod of an electric-arc lamp, of a collar or shoulder thereon, a contact-point in the path of said collar to contact therewith at a predetermined point in the descent of the rod, and mechanism released at the moment of contact between the said collar and contact-point, adapted to impel the contact-point in the direction opposite to the normal movement of the carbon, the collar being connected with one terminal of the lamp and the contact-
50
55

point with the other terminal thereof, substantially as described.

2. The combination with the carbon-rod of an electric-arc lamp, of a collar thereon, a contact-point in the path of the collar to raise
60 the same, and mechanism connecting the contact-point with the feeding mechanism of the lamp adapted to move the contact-point in the same direction as the carbon-rod, the carbon-rod being connected with one terminal of
65 the lamp and the said contact-point with the other terminal thereof, substantially as de-
scribed.

3. The combination in an arc-lamp having a feeding-lever and a spring controlling the
70 same to raise the carbon-rod, and an electro-
magnet opposing said spring in its action upon the feeding-lever, of a collar upon the carbon-rod, a contact-point upon which the collar is adapted to rest when the carbons are
75 consumed, and a connection between the contact-point and the feeding-lever to move the contact-point in the same direction as the carbon-rod when the magnet is de-energized,
80 substantially as described.

4. The combination in an electric-arc lamp having a feeding-lever actuated by a spring to lift the carbon-rod and having an electro-
85 magnet adapted to oppose the spring when energized, of a collar upon the carbon-rod, a contact-point in the path of the collar adapted to connect with it when the carbons are con-
sumed, and mechanism connecting the contact-point with the feeding-lever, adapted to cause the contact-point to move through a
90 greater range than and in the same direction as the carbon-rod, the said contact-point being connected with one terminal of the lamp and the carbon-rod with the other terminal thereof, substantially as described.

5. The combination with the carbon-rod, of a collar moving therewith, a switch in the path of the collar, a normally-excited electro-
95 magnet adapted to cause the movement of said contact in the direction of normal move-
ment of the carbon, and a shunt of the said magnet controlled by the said switch-contact and collar, substantially as described.

In witness whereof I hereunto subscribe my name this 30th day December, A. D. 1893.

CHARLES E. SCRIBNER.
